US00D802532S

(12) **United States Design Patent** (10) **Patent No.:** **US D802,532 S**
Maurer et al. (45) **Date of Patent:** **** Nov. 14, 2017**

(54) **CYLINDER ASSEMBLY**

(71) Applicant: **Parker-Hannifin Corporation**,
Cleveland, OH (US)

(72) Inventors: **Garrett M. Maurer**, Maplewood, MN
(US); **James R. Prazak**, White Bear
Lake, MN (US)

(73) Assignee: **Parker-Hannifin Corporation**,
Cleveland, OH (US)

(**) Term: **14 Years**

(21) Appl. No.: **29/526,552**

(22) Filed: **May 11, 2015**

Related U.S. Application Data

(63) Continuation of application No. 29/454,987, filed on
May 16, 2013, now Pat. No. Des. 732,473.

(57) **CLAIM**

The ornamental design for a cylinder assembly, as shown
and described.

DESCRIPTION

FIG. 1 is a front top perspective view of a cylinder assembly
showing our new design.

FIG. 2 is a front bottom perspective view thereof.

FIG. 3 is rear top perspective view thereof.

FIG. 4 is rear bottom perspective view thereof.

FIG. 5 is a front view thereof.

FIG. 6 is a rear view thereof.

FIG. 7 is a right side view thereof.

FIG. 8 is a left side view thereof.

FIG. 9 is a top view thereof; and,

FIG. 10 is a bottom view thereof.

The broken line portion of the figure drawings is included to
show unclaimed subject matter only and forms no part of the
claimed design.

1 Claim, 8 Drawing Sheets
